UNITED STATES PATENT OFFICE.

LUKE MOFFATT AND CHARLES H. MOFFATT, OF VERNDALE, MINNESOTA.

BUNDLE CARRIER AND DROPPER FOR HARVESTERS.

SPECIFICATION forming part of Letters Patent No. 352,768, dated November 16, 1886.

Application filed August 14, 1885. Serial No. 174,764. (No model.)

To all whom it may concern:

Be it known that we, LUKE MOFFATT and CHARLES H. MOFFATT, of Verndale, in the county of Wadena and State of Minnesota, 5 have invented a new and useful Improvement in Bundle-Carriers for Harvesters, of which the following is a specification.

This invention is an improved bundle carrier and dropper for use with harvesting-ma-10 chines; and it consists in certain features of construction and novel combinations of parts, as will be described and claimed.

In the drawings, Figures 1 and 2 are re-15 spectively front and side elevations of our im-
provement.

In the operation of the harvesting devices the grain is discharged onto a platform, *a*, which in the construction shown inclines downward toward its outer end, so the grain will 20 discharge by gravity when the retaining apron, presently to be described, is released.

In the construction shown beams *c* constitute what may be termed the "framing" or "main frame," for supporting the several other 25 parts of the improvement and facilitating the attachment thereof to a harvester. The beams *c* are the base-beams, and on them we mount the standards *c*⁵, which have their upper edges adapted to receive the top beam of the apron, 30 preferably by notching said standards at 1 to receive the ends 2 of the top beams, *c*¹, of the aprons *b*. This construction is preferred, because by it the apron may be easily removed when desired, and it is also preferred to incline the standards from their lower to their 35 upper ends outward toward the apron, to enable the movable connections, presently described, to slide more easily thereon. The apron *b*, as shown in Figs. 1 and 2, is formed 40 of suitable flexible material—such, for instance, as canvas—and has at its upper end a beam, *c*⁴, supported in standards *c*⁵, while at its lower end it is re-enforced by a beam, *c*², which gives it rigidity at such point, as well as weight, 45 which is especially desirable in the construction shown in said Figs. 1 and 2. To the lower edge or end of the apron are secured at one end connections *m*, which extend forward to and are connected with and movable along the standards *c*⁵. This movable connection with the standards is preferably effected by rings *l*, as shown.

The standards are arranged in front of the apron, and when the apron is closed to collect 55 the bundles or grain the beam *c*² and connec-

tions *m* rest flat against platform *a*, as shown in Fig. 1. When the lower edge of the apron is raised, as shown in Fig. 2, the connection *m* may slide upward on the standards; or, if but a slight movement of the apron be needed, 60 or the connections *m* be made of sufficient length to permit the lower edge of the apron to swing upward, the forward ends of the connections might be fixed rigidly to the standards, or otherwise to the framing. We prefer 65 to connect them with the standards movably, as before described, as thereby the upward movement of the apron is rendered freer and the operation may be accomplished with greater ease. While the apron may be released by 70 hand, it is preferred to employ the cord *f*, secured at one end to the lower end of the apron, and passed thence upward outside of the apron, then at *h* over the top beam of the apron and into convenient reach of the driver, so that 75 the apron may be raised from the driver's seat and will fall by gravity when released.

Having thus described our invention, what we claim, and desire to secure by Letters Patent, is—

1. The combination, with the apron, of the standards arranged in front of the lower edge of said apron, and connections secured at one end to the lower end of the apron, and having their other ends engaged with and movable 85 on the standards, whereby the apron will rest normally in position to secure the grain and may be elevated to discharge the same, substantially as set forth.

2. In combination with the apron; the stand- 90 ards arranged in front of the apron and inclined from base to top toward the apron, and connections secured at one end to the lower end of the apron and held to and movable along the inclined standards, substantially as 95 set forth.

3. The combination of the framing, the apron, a beam supporting the upper edge of the apron, a cord connected with the lower edge of the apron and passed upward outside 100 of the apron and over the top beam thereof, standards arranged in front of the apron, and connections secured at one end to the apron and movably connected at their opposite ends with the standards, substantially as set forth. 105
